UNITED STATES PATENT OFFICE.

HENRY A. MATTHEWS, OF WATERBURY, CONNECTICUT.

METAL TABLE.

SPECIFICATION forming part of Letters Patent No. 315,310, dated April 7, 1885.

Application filed March 13, 1884. (No model.)

To all whom it may concern:

Be it known that I, HENRY A. MATTHEWS, of Waterbury, in the county of New Haven and State of Connecticut, have invented a new 5 Improvement in Metal Tables; and I do hereby declare the following, when taken in connection with accompanying drawings and the letters of reference marked thereon, to be a full, clear, and exact description of the same, 10 and which said drawings constitute part of this specification, and represent, in—

Figure 1, a side elevation, partly in section; Fig. 2, a top view; Fig. 3, a partial section through the top, full size.

15 This invention relates to an improvement in ornamental tables especially adapted for game and like purposes, where small tables are desirable; and the invention consists in the construction of the table, as hereinafter described, 20 and more particularly recited in the claim.

For the top of the table I construct a wood body, A, recessed upon its upper side to leave a surrounding ledge, a. The edge or periphery of this body is molded of any desirable pattern. Onto this body a metal scalp, b, is applied, its central portion sunk so as to lie upon the top of the body and cover the ledge a, the outer edge of the metal wrought into molded shape corresponding to the edge of the body 25 and its extreme edge turned beneath the body, the under side of the body preferably first covered with sheet metal d, which is secured to the body by the overlapping edge e of the scalp.

Instead of molding the edge of the body to 30 correspond to the scalp, the edge may be left plain, the scalp molded upon a form independent of the body. The sheet-metal top is rolled to impress the figures or diagrams for games, here represented as checkers. The impression 35 is made without disturbing the general plane of the table—that is to say, as seen in Fig. 3, the squares which represent the black squares have the figures struck below its general plane; but the depressions are so slight as not to interfere with the general plane of the square, that 40 plane being the same as the white squares—that is to say, the figures which indicate the position of the men in a game are formed with depressions less in area than the figure, the

50 salient portions of the figure retaining the general plane of the surface of the board. These depressions may be in the shape of flowers, birds, or other figures; or they may be simply impressed, so as to produce what is known as a "matted surface." This method of preparing the top not only makes it highly ornamental, but useful in that it prepares the surface for the game in a highly ornamental manner and without interfering with the playing. The rolls for making the sheet for the 55 top of the table have their surfaces prepared according to the ornamentation desired.

In other games—backgammon, for illustration—the figures will be made of the usual shape. Alternate figures are impressed upon 60 the surface, as described, for the squares in the checker. The standard or support for the table is also made from sheet metal. This consists of a central column, B, made from tubing, and ornamental sections D E, made from 65 sheet metal, as shown. The said parts are set together and secured to each other and to the table by a central rod, F, running up through the standard into a head, G, upon the under side of the table.

To the ornamental sections D E legs H are attached—three or more. These legs are made from tubing, as shown, the ends tipped with ornaments and secured to the ornamental sections by screws f, and by surrounding ornamental bands h, attached to the sections or otherwise. By this construction I am enabled to 75 make the table complete from metal, and of a highly ornamental character, and it being made from tubing and spun sheet metal is 80 cheap and durable.

The standard may be improved by making parts of the sections from pottery. I therefore do not wish to be understood as limiting my invention to an entire metal standard.

85 The metal table-top having its surface impressed with requisite figures for games, may be applied to other standards than that herein described.

I do not wish to be understood as claiming, 90 broadly, a metal-top table, or a metal panel having recesses formed therein to receive and indicate the position of men in a game; neither

do I wish to be understood as claiming forming the parts of furniture in sections of tubing, as such I am aware are not new.

I claim—

- 5 The herein-described sheet-metal top or scalp for tables, having figures defined thereon to indicate the position of men in a game, the surface of said figures impressed to form an uneven surface, the depressions being less

in area than the figure, the salient parts of the figure retaining the same general plane as the surface of the table-top, substantially as described.

HENRY A. MATTHEWS.
